UNITED STATES PATENT OFFICE.

MARY ELIZABETH BUDGE, OF NEWTON, AUCKLAND, NEW ZEALAND.

HYGIENIC COVER FOR SANITARY AND OTHER VESSELS.

1,362,671.

Specification of Letters Patent. Patented Dec. 21, 1920.

Application filed December 26, 1917. Serial No. 208,795.

To all whom it may concern:

Be it known that I, MARY ELIZABETH BUDGE, a citizen of the Dominion of New Zealand, and residing at 18 East street, New-
ton, Auckland, in the Provincial District of Auckland, in the Dominion of New Zealand, have invented certain new and useful Im-
provements in Hygienic Covers for Sanitary and other Vessels, of which the following is
a specification.

This invention relates to a cover for san-
itary vessels such as slop-pails, bedpans and
other vessels used in hospitals, private houses
and elsewhere.

The invention consists of a cover made of
a double thickness of canvas or the like, so
that a pocket is formed wherein disinfectant
is stored.

The details for applying the invention to
various vessels are set out in the accompany-
ing drawing, wherein:

Figure 1, is a sectional elevation, and

Fig. 2, is a plan of a slop-pail embodying
the invention,

Fig. 3, is a sectional elevation, and

Fig. 4, a plan of a bedpan embodying the
invention, and

Fig. 5, is a sectional elevation, and

Fig. 6, is a rear elevation of a bedpan
showing a modification of the invention,
and

Fig. 7, is a perspective view of a chamber
embodying the invention.

The shape of the cover and means for
fastening the same vary to suit the vessel
to be covered.

Referring more particularly to Figs. 1
and 2 wherein the cover is shown applied to
a slop-pail, two semicircular parts 1 and 2
40 extend over the top of the slop-pail 3. Each
part 1 and 2 is made of a double thickness
of canvas forming pockets 4 and 5, where-
in any suitable disinfectant is stored. Rods
6 and 7 are fastened to the folds of the parts
45 1 and 2 respectively, which parts are fas-
tened together by a loop or strap 8. The
ends of the rods rest upon the rim of the
slop-pail 3 and support the parts 1 and 2.

The curved edges 9 and 10 of the cover are
stiffened by curved rods 11 and 12 respec- 50
tively. The parts 1 and 2 are held taut by
the rods 6, 7, 11 and 12 and prevented from
sagging with the weight of the disinfectant
contained in the pockets 4 and 5. On the
middle part of the curved edges 9 and 10 55
fastenings consisting of tapes 13 and 14 are
provided respectively for fastening the said
parts 1 and 2 to the ears 15 of the slop-pail,
and these said fastenings are used for sus-
pended the cover when not in use, upon a 60
wall or elsewhere.

The cover is adapted for use upon a bed-
pan 16 as shown in Figs. 3 and 4 by provid-
ing a pocket 17 extending over the body of
the bedpan and with loops 18 at its open 65
end for suspending the cover when not in
use, and by providing another pocket 19 to
fit upon the toe 20 of the bedpan.

The cover as shown in Figs. 5 and 6 has a
pocket 21 extending over the bedpan 22, a 70
fringe 23 fitting around front of the bedpan
and having a gap 24 to receive the handle
24^a, and tapes 25 for fastening the fringe
below the handle 24^a.

The cover is adapted for use upon a cham- 75
ber 26 as shown in Fig. 7 by providing a
pocket 27 extending over the top of the
chamber, the said pocket having an opening
28 for the introduction of a disinfectant.
A fringe 29 has a vertical gap 30 at the back 80
so that the cover can be readily slipped upon
the chamber and secured by a fastener con-
sisting of tapes 31 below the handle 32.

What I do claim and desire to secure by
Letters Patent of the United States is:— 85

A cover comprising a pocket containing
a disinfectant and adapted to cover a bed-
pan, and a pocket fitting upon one end of the
bedpan, substantially as set forth.

In testimony whereof I have signed my 90
name to this specification in the presence of
two witnesses.

MARY ELIZABETH BUDGE.
